SAFETY RAZOR

Felix J. Lewando, Boston, Mass., assignor to Gillette Safety Razor Company, Boston, Mass., a corporation of Delaware

Application June 23, 1943, Serial No. 491,957

7 Claims. (Cl. 30—71)

This invention relates to safety razors of the type in which a thin flexible blade is clamped for shaving between co-operating cap and guard members. The invention consists in an improved construction whereby a blade having a protective envelope or wrapper may be presented to the razor and advanced into its final shaving position and then preliminarily or temporarily held in place to afford the user an opportunity of removing the blade wrapper preparatory to 10 clamping the blade for shaving.

The shaving edge of a thin safety razor blade is brought to such a high degree of fineness that it is extremely delicate and its keenness is likely to be destroyed if the edge is accidentally drawn across any part of the razor or the blade magazine or even the blade wrapper preparatory to 15 shaving. Great care and considerable skill is required ordinarily on the part of the user to extract such a blade from its wrapper and present it safely in its shaving position without damage to its edge. The present invention deals with blades of a type which may be protected at the time of manufacture by being enclosed in a foil or paper wrapper. This wrapper overlaps and safeguards the sharp edge or edges of the razor blade and must be removed to make the edge accessible for shaving. We contemplate 20 a safety razor so organized that the wrapped blade may be delivered directly thereto in its final shaving position and temporarily held as thus positioned while the user has only to strip the wrapper from the blade and withdraw it from the razor, all this being effected without danger and even without the possibility of touching 25 the keen cutting edge of the blade.

The construction of my invention is such that the elements which have been heretofore found regularly in safety razors and with which the public is entirely familiar may be utilized by 40 suitable modification to perform the function of temporarily holding and releasing the blade independently of the clamping movement of the razor parts.

With this end in view an important feature 45 of the invention consists in providing a projecting detent upon one of the blade-clamping members of the razor, the latter being shaped to bow a flexible and apertured blade interposed between them into interlocking engagement with the 50 detent. The blade is presented in substantially flat position and then, as a preliminary step, bowed into engagement with the detent and so held or anchored against longitudinal movement while the user withdraws the blade wrapper.

In accordance with my invention a razor handle of usual exterior design is provided with a threaded connection with one of the blade-clamping members, preferably and as herein shown with a cap, by which the said member may be either drawn into blade-clamping position or held in a position spaced above the blade. The other member, in this case the guard, is so constructed and arranged that it may be then freely moved toward the cap and the blade bowed into engagement with the detent. As another feature the threaded connection includes a stop which determines the extent of free movement of the blade-clamping members toward and from each other. The two members may therefore be moved toward each other under finger pressure of one hand bowing the blade and temporarily anchoring it as above explained. While the blade is so held the user may withdraw its protective cover or wrapper with the other hand and as soon as this is done the bare blade is ready to be securely clamped in shaving position.

These and other features of the invention will be best understood and appreciated from the following description of a preferred embodiment thereof selected for purposes of illustration and shown in the accompanying drawing, in which:

Fig. 1 is a view in perspective of a protected blade suitable for use with the safety razor herein shown and described;

Fig. 2 is a view in perspective of the complete razor illustrating the operation of withdrawing the protective cover from a blade while the cap and guard are held under finger pressure;

Fig. 3 is a view in perspective of the razor in shaving condition with a blade clamped therein;

Fig. 4 is a perspective view showing all the component parts of the razor in exploded relation;

Fig. 5 is a view of the razor in longitudinal section on an enlarged scale corresponding to Fig. 2;

Fig. 6 is a view in cross-section of the razor on an enlarged scale showing the cap and guard separated; and

Fig. 7 is a similar view showing the cap and guard in fully clamped condition.

The razor selected for illustration is of the "Gillette" type although the invention is not restricted to that or to any other particular type of safety razor. As herein shown, however, the razor comprises co-operating blade-clamping members of which the cap member 10 is substantially rectangular in contour with a concave inner face from which projects a flattened stem

11 and a pair of aligned blade-locating ribs 12. One end of the cap is provided with a wide notch 13 to facilitate presentation and removal of a blade from the razor. The stem 11 is surrounded by a detent 14 which is circular in cross-section and of somewhat less height than the blade-locating ribs 12. In the assembled razor the stem 11 of the cap is permanently connected to the upper forked end of a threaded stem section 15. For this purpose the stem 11 is provided with a pair of spaced transverse perforations. Permanent connection between the two parts is made by slipping the flattened stem 11 into the groove or slot of the stem section 15 and then swaging the metal of the latter so that it is caused to flow slightly into the perforations of the stem 11 as indicated in Figs. 4 and 7.

The other blade-clamping member of the razor, that is to say, the guard 22, is similar in outline to the cap except that it is somewhat wider. Its upper face is convex being provided with fulcrum shoulders which lie inside the marginal edges of the cap 10 and over which a flexible blade may be bowed when the cap and guard are moved toward each other. The outer edges of the guard are curved outwardly and downwardly to form guard bars and the upper surface of the guard is provided with an elongated diamond-shaped depression 23 which affords clearance for the blade-locating ribs 12 of the cap. The ends of the depression 23 are slotted to accommodate the outer ends of the ribs 12. The guard 22 is permanently secured to the upper end of a sleeve 16 having a collar which engages the outer or under face of the guard. The upper end of this collar is spun into a slightly countersunk perforation in the guard.

The razor handle comprises an elongated barrel 17 having a shouldered internally threaded portion 18 which is engaged with the threaded portion of the stem section 15 of the cap. The handle is provided in its upper end with a longitudinal bore or bearing for the sleeve 16. The sleeve 16 with its attached guard is freely movable longitudinally in this bearing when permitted to do so. The stem 15 is threaded into the threaded portion 18 of the barrel 17 and a stop screw 19 with an enlarged head is then inserted in the end of the stem section 15 and arranged to bear upon a shoulder in the barrel 17 which marks the lower end of the threaded portion 18 when the cap and guard occupy their positions of maximum separation. The screw 19 may be reached by a screw driver inserted longitudinally in the bore of the barrel 17 when it is desired to assemble the razor parts as above described.

In Figs. 1 and 4 are shown a blade 25 of suitable design for use with the illustrated safety razor. The blade is double-edged, constructed of thin flexible steel and recessed at each of its corners to provide elongated unsharpened end portions. The blade is provided with an open-ended slot 26 which includes several enlargements of which the central aperture is designed to fit the circular or cylindrical detent 14 of the cap. The blade is herein shown as protected by a folded cover 27 of paper or foil extending beyond the sharpened edges of the blade and shaped to leave the blade slot 26 unobscured.

When it is desired to insert a blade in the razor the handle barrel is rotated in a counter-clockwise direction elevating the stem 11-15 and its cap until arrested by the stop screw 19. Fig. 6

represents the cap and guard thus positioned and it will be apparent that the protected blade may now be inserted endwise in flat condition without disturbing its protective cover 27. In this movement of presentation the open-ended slot permits the sides of the blade to pass upon opposite sides of the flattened portion of the stem above the end of the cylindrical stem section 15. When the protected blade has been thus positioned in the razor the cap and guard are squeezed together by the fingers of the left-hand as indicated in Fig. 2. In response to this pressure the guard 22 and its sleeve 16 are moved upwardly, the sleeve 16 sliding freely in the bore of the handle barrel 17. Consequently, the interposed blade 25 is bowed so that its central aperture becomes interlocked with the detent 14 and the blade is thus positively locked against longitudinal movement. This is the condition of the razor as illustrated in Figs. 2 and 5. The user may now engage the projecting end of the cover 12 and withdraw it from the blade leaving the latter located safely in its shaving position. Finally the handle barrel 17 is rotated in a clockwise direction and the threaded stem 11-15 with the cap member 10 is drawn downwardly until the blade is positively clamped in transversely curved position as shown in Fig. 7. In this position it will be noted that the head of the stop screw 19 is separated from the shoulder defining the threaded portion 18 in the razor handle.

Having thus disclosed my invention and described in detail an illustrative embodiment thereof I claim as new and desire to secure by Letters Patent:

1. A safety razor comprising cap and guard members, one of which has a projecting detent and the other a substantially convex blade-supporting surface, a threaded spindle rotatable to draw said members into blade-clamping relation or to release them for relative movement toward or from each other in a limited definite path under finger pressure, whereby an interposed perforated blade may be bowed into interlocking engagement with said detent and so held while a protective cover is withdrawn from the blade.
2. A safety razor comprising cap and guard members shaped to bow a flexible and perforated blade interposed between them, one of said members having a detent, and screw threaded connections for drawing said members together, said connections being releasable to free the said members for limited relative movement toward and from each other under finger pressure to bow a blade into engagement with said detent.
3. A safety razor comprising cap and guard members shaped to bow a flexible and perforated blade interposed between them, the cap having a shallow projecting detent on its inner face, and a handle having a threaded connection with the cap member by which the cap may be held in a blade-clamping position or in a position spaced above the blade, the guard being then movable toward the cap whereby the blade may be bowed into engagement with said detent.
4. A safety razor comprising cap and guard members shaped to bow a flexible and perforated blade interposed between them, the cap member having a detent on its inner face, a handle connected to the guard member and having an internally threaded portion, and a threaded stem on the cap engaged with the handle and having a stop limiting the separation of the cap from

the guard member, and means for guiding the guard member for movement toward the cap for preliminarily bowing a blade into engagement with said detent.

5. A safety razor comprising cap and guard members shaped to bow an apertured flexible blade interposed between them, the cap having a detent on its inner face, a handle having sliding connection with the guard member and having an internally threaded part, a threaded stem projecting from the cap into said handle and engaged with the threaded part thereof, and a stop screw in the end of the stem for limiting separation of the cap and guard while leaving them free to be moved together to bow a blade into engagement with said detent.

6. A safety razor comprising cap and guard members shaped to bow an apertured flexible blade interposed between them, the cap having a detent and a threaded stem, the guard having 10

15 a tubular sleeve surrounding said stem, a handle having a bearing in which the sleeve slides and a threaded portion engaged with the stem of the cap, and a stop on the stem for limiting separation of the cap from the guard.

7. A safety razor comprising cap and guard members having respectively blade-shaping faces which are generally concave and convex, the cap having on its inner face a blade-locating rib, a detent and a threaded stem, the guard having a tubular shank, and a handle having a longitudinal bearing at its end in which slides the tubular shank of the guard member and a threaded part engaged with said threaded stem, and a limit stop at the end of said stem for determining the position of maximum separation of the cap from the handle, the guard meanwhile being movable between the cap and handle.

FELIX J. LEWANDO.
